UNITED STATES PATENT OFFICE.

GUSTAF DAVID SUNDSTRAND, OF ROCKFORD, ILLINOIS, ASSIGNOR, BY MESNE ASSIGNMENTS, TO SUNDSTRAND MACHINE TOOL CO., OF ROCKFORD, ILLINOIS, A CORPORATION OF ILLINOIS.

GRINDING MACHINE.

Application filed March 30, 1925. Serial No. 19,198.

This invention relates to grinding machines and particularly to a universal grinding machine involving means for grinding circular arcs and surfaces of a large radius. 5 The grinding machine art abounds with various universal machines, but those which are equipped for radius grinding are few in number and are at the most large and cumbersome, occupying considerable floor space because of the provision of the radial grinding mechanism. Such machines are usually specially adapted for radial grinding and are not generally adapted for other common forms of grinding work. A radius grinder 10 is a specially valuable machine for use in a railroad shop where the links of locomotives are ground, so that by providing other facilities in the machine, the radius grinder is not only special equipment, but is also useful universally.

It is an object of the present invention to provide a universal machine of the character above referred to which is especially adapted for use in railroad shops.

25 It is a particular object of the invention to provide a novel arrangement permitting the grinding of circular arcs with a large radius.

It is another object of the invention to provide a machine in which the radial grinding 30 members occupy very little floor space.

A still further object of the invention is to provide a radius bar in the machine which is vertically suspended from a rigid upright extension of the base.

35 Another object of the invention is to provide a horizontally movable work carriage which operates in conjunction with the radius bar to produce an arcuate path for the work past a grinding wheel.

40 A further object of the invention is to utilize the horizontally movable carriage for ordinary grinding as in other types of grinding machines providing both hand feed and automatic feed to said carriage.

45 A still further object of the invention is to provide the grinding wheel with a movable carriage having a hand and an automatic feed, to provide vertical adjustment of the grinding wheel on its carriage and to provide 50 a planetary motion for the grinding spindle.

A still further object is to provide a particular type of planetary mounting to permit adjustment of eccentricity of the spindle from zero to a maximum.

Still other and ancillary objects will appear 55 in the ensuing description.

By providing a machine capable of carrying out the foregoing objects I may produce a universal grinding machine suitable for radius grinding, internal grinding, surface 60 grinding, and cylindrical grinding.

In the accompanying drawings I have illustrated a machine embodying the principles of the invention which fulfills all the foregoing objects and which has other and ancillary advantages as will be apparent from the ensuing 65 description.

In the drawings, Figure 1 is a front elevation showing the front of the work base and the end of the grinder spindle base. 70

Fig. 2 is a side elevation looking toward the right in Fig. 1, showing the end of the work base and the front of the grinder spindle base.

Fig. 3 is a plan section taken approximately on the line 3—3 of Figs. 1 and 2 showing 75 the important features relating to power distribution.

Fig. 4 is an enlarged front elevation of the work base showing the mechanism in the gear box in cross section and showing a piece 80 of work set for radius grinding.

Fig. 5 is a vertical cross section of the work base taken approximately on the line 5—5 of Fig. 4 showing the construction of the work table and of the work carrier and the 85 automatic drive mechanism for the table.

Fig. 6 is a side elevation of the spindle base showing power drives in dotted lines and showing a cross section of the gear box.

Fig. 7 is a front elevation of the end of the 90 spindle base showing another cross section of the feeding mechanism in the gear box, the power drives, and the coolant pump.

Fig. 8 is a cross section of the spindle casing and of the parts showing the arrangement for 95 the planetary drive, the cross section being taken along the line 8—8 of Fig. 10.

Fig. 9 is a detail cross section on line 9—9 of Fig. 8 showing the interior of the spindle casing and the vertical feeding means therefor. 100

Fig. 10 is a cross section of the front end of the spindle casing on the line 10—10 of Fig. 8 showing the planetary drive and planetary adjustment.

Fig. 11 (Sheet 2) shows a detail view of the 105 power connection used in the planetary drive, the view being an enlarged portion of a corresponding part in Fig. 1.

Figs. 12 and 13 (Sheet 4) represent front and side views of a locking device for the work table.

Fig. 14 (Sheet 7) is a diagrammatic explanation of the radius grinding principle.

General description.

The machine illustrated in the drawings comprises generally a horizontally movable 10 grinding wheel carriage and a horizontally movable work table or carriage. Each of said carriages has vertical ways thereon upon which the wheel head and the work are vertically adjustable and movable. A radius arm 15 is pivotally connected to the machine frame and to a work carrier which is movable on vertical ways on the work table. By this construction the horizontal reciprocation of the work table produces a vertical reciprocation 20 of the vertical work carrier, the two motions being thus compounded into a single arcuate motion resulting from a harmonic motion vertically with respect to uniform motion horizontally.

25 The grinding wheel carriage is equipped to have an automatic reciprocating motion and in addition a continuous oscillatory motion superimposed upon the reciprocation. It is further provided with other adjustments for 30 horizontal and vertical positioning of the wheel with relation to the work. In addition the grinding spindle has a planetary drive, and an adjustment whereby the spindle may be offset a predetermined distance from a 35 given axis and thereupon revolved in an orbit about said axis. These features adapt this portion of the machine for universal grinding.

40 Both the horizontal work table and the vertical work carrier thereon are equipped to receive and to hold work by the application of suitable fixtures thus adapting the machine to hold work in that position best suitable for location with respect to the grinding wheel 45 for any particular operation.

Base and power distribution.

Referring particularly to the machine illustrated in the drawings there is shown a machine supported by a base substantially in the 50 form of a cross (Fig. 3). The base comprises preferably a plurality of sections as 10, 11 and 12 (Fig. 3) which are bolted together. The base section 10 supports the work carriage. The base section 11 is in reality an 55 upright column, the upper portion of which has two rectangularly arranged faces 13 and 14, tapering toward their common edge at the top. This column provides a rigid support for the upper end of the radius bar. The base 12 supports the grinding wheel carriage and carries its related mechanism. An 60 ancillary structures are suitably arranged in the assembly unit to interrelate the principal parts of the machine for universal coopera-

tion to provide a machine of the character desired.

The machine is preferably self-contained and to this end is provided with a motor 15 (Figs. 1, 2 and 4) carried by a bracket 15^a 70 (Fig. 4) on the column 11. A main drive shaft 16 (Fig. 3) is provided near the bottom of the machine from which a grinding wheel is indirectly driven and the carriages are fed. The shaft 16 carries a power receiving 75 pulley 17 driven by a belt 18 from the motor.

The shaft has its driven end suitably supported transversely through the base section 10 by bearing 19, while the other end bears 80 in a supporting arm 20 secured to the end face of base section 12. A wide pulley 21 is carried by the shaft adjacent to said arm for a belt drive to the grinding wheel. For travelling the two carriages the countershaft 22 is provided transversely to the main shaft, 85 intermeshing helical gears 23 and 24 being provided on said shafts, as shown in Figs. 2, 3 and 6. This countershaft 22 is provided with a pulley 25 for driving a pump 26, a 90 bevel gear 27 for certain of the grinder carriage mechanism, and a set of cone pulleys 28 for operating the work carriage mechanism through belt 29 to a set of larger cone pulleys 30 on a parallel countershaft 31. A pulley 32 95 on this shaft connects by means of belt 33 to another part of the grinder carriage mechanism. This last mentioned mechanism effects the reciprocal motion of the grinding 100 wheel while the shaft 31 effects the reciprocal motion of the work. It will be understood, of course, that other means of power distribution may be employed.

The parts hereinabove referred to disclose but one power shaft 31 to the work end of the machine while there have been disclosed three power driven movements to the grinding wheel end, namely, the main shaft pulley 21, the bevel gear 27 on countershaft 22, and the pulley 32 on the second countershaft 31. 105 These three power sources operate independently upon the grinding wheel, each one, however, being capable of governing the motion thereof in a predetermined manner. The main pulley 21 effects rotation of the grinding wheel as well as a planetary motion to the wheel spindle. The bevel gear effects a continuous oscillatory motion of the wheel 110 axially of the spindle to prevent uneven wear of the grinding surface. The pulley 32 effects the automatic reciprocal travel of the grinding wheel axially thereof into and out of or along the work.

Grinding wheel mounting.

The structure of the grinding wheel mounting herein disclosed comprises a horizontal carriage 34 (Figs. 1, 2 and 6) movable on ways 35 at the top of the base section 12. This carriage bears an upright head 36 which is 130

provided with parallel vertical ways 37 upon which slides the spindle mounting or casing 38 shown in detail in Fig. 8. Vertical adjustment is obtained by any suitable means as, for example, a fixed worm screw 39 (Figs. 2, 8 and 9) carried in the upright head 36 and the bevel gear-nut 40 threaded thereon and rotatably fixed in a bracket 41 carried by the spindle casing 38. Nut 40 is rotated in its bracket by the bevel gear 42 on shaft 43 which carries the hand wheel 44 by which vertical adjustment is effected.

The spindle employed may have any well known construction. However, for the purposes described I prefer to provide a spindle which has a planetary motion, the same being placed eccentrically in the casing 38, and I further provide means to effect an adjustment in the eccentricity from zero to a maximum. Such a construction provides a machine which is more universal in character than would follow from the provision of a fixed spindle. Herein in Figs. 8-11 I illustrate a suitable type of planetary mechanism contained within the casing 38. A suitable shaft 45 is adapted for driving a grinding wheel 46 at one end thereof, a small wheel 46 being herein shown. The shaft 45 is belt driven over the pulley 47 at one end thereof. The grinding wheel spindle is preferably made in two separable sections in axial alignment, one section being the shaft 45 and the other being a removable section 48 to provide for using various types of grinding heads on the casing 38. The removable spindle section 48 carries the wheel 46 and abuts the spindle section 45 in a universal slot and key joint 49. Shaft 45 is eccentrically and rotatably mounted in a shell member 50, suitable anti-friction bearings 51 and 52 being provided at each end of the spindle. Shaft 48 is rotatably mounted in a removable casing or head 53 which has a cylindrical projection 54 thereon fitting into a corresponding recess eccentric of the shell 50. The end of projection 54 and the recess are threaded as at 55 to secure a tight fit of the parts. The shell 50 is also eccentrically and rotatably mounted in a housing or sleeve 56 which is rotatable with respect to the casing 38, the axis of rotation of housing 56 being coaxial to the casing 38 (Fig. 9). The distance off-center of the spindle in shell 50 is the same as the distance off-center of shell 50, in housing 56. By this arrangement the eccentricity of the spindle with respect to member 56 (and hence the casing 38) becomes variable from zero to a maximum according as the shell 50 is turned relative to the housing 56. Therefore, in one position of the spindle (Figs. 9 and 10) the spindle 45 is centered with the axis of the housing 56 because the eccentricities neutralize each other, while in another position (Fig. 9) the spindle indicated in dotted line has a maximum eccentricity produced by

turning shell 50 180° about its axis from the neutral or full line position indicated.

Means is further provided to effect a variation of the eccentricity by rotation of the shell 50 with respect to its housing member 56. This means comprises a worm gear 57 fixed to the shell 50 and a worm pinion 58 in mesh therewith carried by the housing member 56 by brackets 58a in which the pinion is rotatable. A pair of bevel gears 59 and 60, one on the pinion, and the other rotatably carried in the face of the housing member 56 and fixed on a shaft 61, serves to effect the adjustment by turning of the shaft. Shaft 61 is provided with suitable means as 80 a key or thumb screw 62 (Fig. 2) for this adjustment of spindle eccentricity.

When the spindle is used in its eccentric adjustment, the housing 56 must be rotated to secure the desired planetary motion. Means is provided for doing this from a power drive through the following described mechanism: Pulley 63 (Figs. 1, 2 and 11) receives power from the belt 64. A short stub shaft 65 carries the pulley 63 and transmits power to a parallel shaft 66 on casing 38 through a short vertical shaft 67. Two sets of helical gears indicated by numerals 68 and 69 make the power connections through shafts 65, 67 and 66. Shaft 66 bears in the casing 38 and is parallel to the axis of the spindle. A spur pinion 70 at the end of shaft 66 meshes with a spur gear 71 keyed at 72 to the housing member 56 axially thereof (Figs. 8 and 10). Spur gear 71 serves as the bracket mounting member for the worm screw 58 which is carried thereby about the spindle as the spur gear rotates. A ring guard 72 is placed over these rotating parts.

The planetary motion of the grinding spindle continually displaces the spindle driving pulley 47. Since the latter is belt driven, suitable means is provided for compensating for the changes in driving distance as traveled by the belt. This is accomplished by the provision of a movable idler pulley which keeps the belt always under the same tension and thereby prevents slack therein as the planetary motion of the driving spindle takes place. The motion of the pulley is controlled by the motion of the spindle. The wide drive pulley 21 (Figs. 1 and 9) carries a belt 73 to the spindle pulley 47, three idlers 74, 75 and 76 being interposed. Idlers 74 and 75 are fixed and idler 76 is movable. The latter is carried by an arm 77 pivoted to the base, in the present instance at the axial center of pulley 75. Pulleys 75 and 76 are arranged so that the belt to and from the grinding pulley 47 is substantially parallel to itself in both parts. A movable link 78 is pivotally supported at both ends, one end being pivoted at 79 which is the longitudinal center of arm 77 between the pulleys 75 and 76 and the other being pivoted about the axis of the grinding

spindle. The horizontal component of the planetary motion of the spindle is thus transmitted through link 78 to oscillate arm 77, moving pulley 76 substantially twice the horizontal displacement of the spindle. This doubling of the motion takes care of the additive slack in both sides of the belt 73. The idler pulley 75 carries externally thereof a smaller pulley 80 integral therewith which is connected by the belt 64 to the pulley 63 which effects the planetary motion of the spindle as above described. In the arm 78 a clamping screw 81 is provided to bind the pivotally related arm 78 and the spindle rigidly together, thus to prevent motion of the planetary mechanism when not desired, this being an effective locking device.

Grinding wheel carriage.

While the grinding wheel has the rotary planetary motion above described, it is important in some respects that it have also an axial oscillatory motion to prevent uneven wear of the wheel surface. Means is provided for this purpose which can be put into and out of operation as desired. The base 12 carries on its inside a feed screw 85 (Fig. 3) bearing in the base at 86 and at 87, the feed screw being slideable axially in said bearings. One end of the feed screw has two separated flange plates 88 and 89. The carriage 34 has a downward projecting portion 90 which carries a nut 91 engaging with said feed screw. Thus, motion of the feed screw rotatably or axially will effect motion of the carriage 34 on its ways 35. Independent means are provided to secure these two motions of the screw. The flanges 88 and 89 provide means to hold the feed screw in the desired axial position. A bracket 92 on the face of base 12 (Figs. 1 and 6) supports at pivot 93 a bell crank having a vertical arm 94 and a horizontal arm 95. Arm 94 is bifurcated and has two opposing pins 96 and 97 which fit between flanges 88 and 89 to hold or to move the feed screw axially according to the position of the bell crank. When the bell crank is stationary the feed screw is stationary. The horizontal arm 95 is arranged to be oscillated to effect a continuous oscillation of the grinding carriage. Suitable means is provided for producing the oscillation from the main shaft. As hereinbefore stated, bevel gear 27 on countershaft 22 effects the oscillatory motion. Bevel gear 27 (Fig. 3) is provided with a clutch device engaging it with shaft 22, said clutch being generally indicated at 98. A drawbar 99 to operate the clutch is shown passing through the base 12 to the front face thereof where a handle 100 is provided thereon. A side casing 101 on the base 12 carries a shaft 102 (Fig. 6) with a bevel gear 103 in mesh with a gear 27 and a worm pinion 104 which is in mesh with a worm wheel 105 on shaft 106 located transversely to the base 12. An eccentric

106^a on said shaft 106 lies in the bifurcated end 107 of bell crank arm 95 whereby to effect the reciprocation.

The carriage 34 may be placed anywhere on its ways by suitable means for hand adjustment of its position. With clutch 98 thrown out of power connection, the feed screw is fixed axially in the base 12 so that the carriage may be moved only through the rotation of the screw 85 in the nut 91. The bearing 87 (Fig. 3), in which the shaft of feed screw 85 is splined, is rotatable and has a bevel gear 108 integral therewith in mesh with a bevel gear 109. This in turn is carried by a shaft 110 which is turned by the usual hand wheel adjustment 111.

Grinding wheel carriage feed.

Automatic reciprocal travel is also provided for the grinding wheel carriage 34 and to this end a gear casing 112 is placed on the base 12 for suitable mechanism to effect this motion (Figs. 3, 6 and 7). The mechanism employed is associated with the feed screw 85 above described and is adapted to rotate said screw to effect the feed through the nut 91 engaging said screw. Because of the oscillatory motion which may be imparted to the feed screw 85 by the arm 94, the feed screw is splined into the mechanism in the feed box 112 by the key indicated at 113 (Fig. 6). The parts of the mechanism directly in splined relation with the shaft constitute the clutch 114 and a bevel gear 115 (Figs. 3 and 6). The bevel gear is rotatably fixed in upright member 116 which provides a bearing therefor within the box 112. The clutch 114 includes a movable element 117 having an annular groove 118 therein. A clutch operating means is provided at the top of the box in the form of a radial handle 119 on a shaft 120 which terminates over the groove 118. A pin 121 eccentrically located in the end of shaft 120 extends into the groove 118 so that turning of the handle 119 controls the motion of the clutch member 117 into and out of operative position. Because of the desired clutch action only the movable clutch member 117 is splined with the feed screw shaft 85, the remaining elements of clutch 114 and the gear 115 being freely rotatable and slideable over said shaft which may thus oscillate with or without rotation.

Rotating and reversing mechanism for bevel gear 115 is provided as shown in Figs. 3, 6 and 7. The belt 33 from pulley 32 of Fig. 3 runs over a pulley 122 on a stub shaft 123 journaled in box 112 at one side thereof. Within the box a spur pinion 124 meshes with a spur gear 125. A shaft 126 in the box is arranged across the end of the feed screw 85. The shaft 126 carries the spur gear 125 fixed thereon and also two loosely mounted bevel gears 127 and 128, each in mesh with opposite sides of the bevel gear 115. Said

two bevel gears are keyed to sleeves 129 and 130 rotatably carried on the shaft 126, the juxtaposed ends of said sleeves being clutch elements. A third sleeve 131 is splined on the shaft 126 by key 132 and is slideable to the left or the right into contact with either one of the sleeves 129 and 130. The ends of sleeve 131 are likewise clutch elements which can thus be moved so that either gear 127 or 128 turns with the shaft 126. An annular groove 133 is provided in the sleeve for receiving a lug 134 which moves the sleeve into and out of position.

Automatic tripping and reversing mechanism is provided between the grinding wheel carriage and the aforesaid mechanism. This is provided as a movable member automatically moved by dogs the positions of which are adjustable to effect a predetermined path for the carriage 34. On the side of the base 12, (Figs. 3 and 6) there is supported a rock shaft 135 with one end bearing in the box 112. Adjustable winged dogs 136 and 137 are secured to the rock shaft 135 by clamping screws 138. Each dog has a wing 139 which is substantially 45° angular to the shaft the wings of both dogs being parallel. Carriage 34 carries a pin 140 which travels a path over the shaft 135 and between the two dogs so as to strike the wings 139 in its journey. The wings act as cams and rock the shaft clockwise at one end and counter clockwise at the other end at the travel of the pin 140. Within the box the end of shaft 135 carries a rigid crank arm 141 (Fig. 7) which is linked to a lever 142 by a connecting link 143. The lever 142 (Figs. 6 and 7) is pivotally supported at 144 on top of the box 112, and is provided with a handle 144^a for manual operation of the lever. Connecting means from lever 142 to the lug 134 is provided as follows: A fixed shaft 145 parallel with shaft 126 has a U-shaped slide 146 thereon, the base of which carries the lug 134 for motion horizontally to move the clutch sleeve 131. A grooved collar 147 is also slideable on the shaft 145 and is positioned between the legs of the U-slide and maintained centrally therebetween by two similar springs 148, one on each side of the collar between it and the adjacent legs of the U-slide 146. The end of the lever 142 is bifurcated and carries pins 148^a (Fig. 6) which lie in the groove of collar 147 to move it. Freely pivoted dogs 149 and 150 moved by gravity lie on the tops of the U-legs, each dog being provided with a shoulder 151 which catches the end of the U-leg as it slides away from the dog and prevents a return thereof toward that end of the shaft 145. The dogs 149 and 150 extend toward the lever 142 which is provided on each side with cam projections 152 and 153 positioned to raise each dog as the lever 142 moves toward it, thereby to release the slide from engagement with the shoulder 151. As the lever 142 is

moved toward the right in Fig. 7, the right hand spring 148 will be compressed tending to move the slide to the right. When the slide moves, dog 150 will drop and its shoulder 151 will prevent the return of the slide. 70 If lever 142 is now moved toward the left, which will be accomplished by the rock shaft 135 or manually through handle 144^a, the left hand spring 148 will be compressed and the slide will not move because of its engagement with the shoulder 151. At the extreme motion of lever 142 the cam 153 thereon will raise the dog 150 and the spring will thereupon cause the slide to move to the left, after which dog 149 will drop to lock it in place. 80 Each such shift of the U-slide 146 carries the clutch sleeve 131 to engage either of bevel gears 127 and 128 and thus accomplishes a reversal of the feed screw 85.

Work table and carrier.

85 The work end of the machine heretofore alluded to comprises a work table or carriage 160 (Fig. 5) movable on ways 161 on the base section 10.

An upright member 162 is 90 removably carried on the table, being bolted thereto at one of several T-slots 163 formed in the table's top surface. Vertical parallel ways 164 are provided on said upright member 162 upon which a work carrier 165 is 95 slideable by means now to be described. T-slots 165^a are provided in the face of the work carrier. The base 11 projecting above the remainder of the machine into a tall column as above described, has a vertical way 166 (Fig. 100 2) thereon upon which a slide 167 is movably supported. The slide has a bracket 168 on the rear side thereof which is threaded as a nut to engage a rotatable feed screw 169 mounted on the column. The feed screw carries at its lower end a bevel gear 170 (Fig. 4) meshing with a bevel pinion 171 carried by a hand wheel 172. By this wheel the slide may be raised and lowered through rotation of the feed screw. A gage bar 173 and a pointer 174 on a bracket 168 indicate the distance over which motion is made in adjusting the position of the slide on the column. The slide 167 carries a pivotal projection or block 175 thereon which carries a radius bar 176 passing therethrough in clamped relationship. A clamp 177 is provided for tightening the radius bar 176 in rigid non-slipping relationship in the pivotally projecting block 175. The radius bar is used to suspend the work 110 carrier 165, a removable lug 178 being provided on the top of the carrier for attachment of the bar. A pivotal bearing 179 (Fig. 5) for a pin 180 on the link 176 is provided. By this construction horizontal motion of the 115 carriage 160 causes vertical motion of the suspended work carrier 165 whereby an accurate path results, the radius depending upon the distance between the pivotal points 175 and 179. 120

Work table feed.

Horizontal travel of the work table 160 is secured by suitable automatic reciprocating mechanism. This is substantially like that disclosed for the grinding wheel carriage. A gear box 181 on the base 10 contains the automatic mechanism shown in detail in Fig. 4. The principal features of the mechanism duplicate that already described for the grinding wheel carriage so that only the specially different features will be here referred to. The driving countershaft 31 extends into the box 181 for operating the gears therein directly by alinement with the gear shaft 182 (Fig. 4). Through the box mechanism, generally designated 183, the power is transmitted to shaft 184 (Fig. 5) which carries the large bevel gear 185 of said mechanism. Between the carriage 160 and the shaft 184 a speed reduction mechanism and a clutch means is suitably arranged. Shaft 184 carries a spur pinion 186 in mesh with spur gear 187 carried on a sleeve 188 rotatable on shaft 189. The end of sleeve 188 has clutch teeth which engage with clutch teeth on a collar 190 slidably splined onto shaft 189. A groove 191 in the collar provides means for an operating member to move the clutch into and out of engaging position. This means is illustrated in Figs. 3 and 4. A vertical shaft 192 within the base 10 carries an arm 193 adapted to move the clutch collar 190 and an operating handle 194 which is located outside of the base 10, passes through a hole 195 provided in the base. Both arms being relatively long, it is an easy matter for the operator to control the carriage motion by moving in or out the handle 194. When the clutch is in, power is transmitted from gear 187 to shaft 189. A spur pinion 196 on shaft 189 meshes with gear 197 on a stub shaft 198 and a rack bar 199 carried by the carriage 160 on the under side thereof meshes with gear 197. Thus, the carriage may move on its bed.

Reversing is accomplished by dogs carried on the carriage. A lever 200 (corresponding to lever 142 on gear casing 112) is pivoted to an upright bracket 201 on the gear casing 181. The manually operated handle 202 of said lever carries a pin 203 which is struck by dogs 204 and 205 adjustably fixed in a T-slot 206 on the under side of carriage 160. The tripping of lever 200 in one or the other direction reverses the gear for the carriage in the manner above described for the grinder mechanism.

In addition to the automatic travel, a hand drive is provided by the provision of a shaft 207 (Figs. 3 and 4) having rigid therewith the hand wheel 208 and a spur pinion 209 in mesh with an intermediate gear 210 on shaft 211, this gear in turn being in mesh with the gear 197 which moves the carriage.

When it is desired to dispense with the motion of the carriage the gear box lever 200 may be left in vertical or neutral position, but to ensure it against accidental tripping, the dogs 204 and 205 may be moved against pin 203 on both sides. However, this does not ensure against motion between the carriage and the bed since turning of hand wheel 208 may trip the lever. Therefore I provide an auxiliary device which may be so clamped with relation to the bed and the carriage that motion cannot result. Such a device is shown in Figs. 12 and 13 (Sheet 4). It is arranged to be clamped to the under side of the carriage by bolts 212 the heads of which may lie in T-slot 206. The device comprises a base portion 213 the ends of which have open slots 214 therewith adapted to receive the shanks of bolts 212. A forked portion 215 extends downwardly from the base 213 and is adapted to fit around shaft 207 of the hand wheel 208. Clamping screws 216 are arranged in the forked portion so as to be screwed onto the shaft 207, thus preventing any play between the device and the shaft, as well as preventing turning of the hand wheel 208. By this device an assured stationary relation between the carriage 160 and its bed is thus attained. In order to permit reciprocation, this device must be removed from the machine.

In the automatic reciprocation of the carriage 160 there is bound to be some lost motion at the end of each travel because of the numerous gears entrained from the power feeding and reversing mechanism. When the work carrier 165 is suspended from the radius bar 176, its weight say in the position indicated in dotted lines of Fig. 1 will tend to move the carriage 160 toward the center. This motion will take place at the end of the travel as soon as the power is disconnected, because of the lost motion in the gears. To prevent this I provide means which hold the parts at the extreme position until the lost motion in the gears has been taken up by the reversal of the gears. The power drive takes up the lost motion and then power moves the table against the force of the holding means. Thus there may be produced a uniform travel in each direction with a short period of rest at the extreme end of the travel while lost motion is being taken up. This is accomplished by a friction device best shown in Figs. 4 and 5. The carriage 160 has a rack bar 217 on its rear side preferably attached to the upright bracket 162. On the column 11 a drum 218 carries an axial shaft 219 with a spur gear 220 at its end meshing with the rack. A friction flange or plate 221 on the shaft 219 bears against the end of the drum 218. Variable pressure is produced between the friction surfaces by the provision of a spring 222 and a nut 223 on the other end of the shaft 219 on the opposite side of the drum.

Many ancillary devices common to machine tools may be added as desired to the machine above described. One such device is shown in Figs. 1, 3, 6 and 7 and heretofore alluded to 5 as pump 26. This is driven from pulley 25 on countershaft 22 by the belt 223. The pump (Fig. 7) has a vertical shaft 224 and a pulley 224^a. The pump 26 includes a centrifugal rotor 224^b which drives the coolant into pipe 10 224^c. The machine is suitably arranged for 15 draining back the liquid to the pump sump in any well known manner.

Operation.

15 For operating the machine a variety of fixtures may be supplied for the varied work required of it. In Figs. 4 and 5 a fixture 225 is shown for clamping a piece of work 226 which in the present instance is a link to be 20 radially ground. The fixture is bolted into the T-slots 165^a in the vertical work carrier. Other suitable fixtures may be substituted either on the vertical or on the horizontal table as required. At the grinding wheel end 25 the spindle head 53 may be removed and replaced by one of another character for any special purpose.

In grinding the piece of work 226 it is held 30 in the fixture 225 by the bolts 227 passing through lugs 228 on the fixture. The grinding wheel indicated by the circle 46 is placed in a stationary position within the cast opening 229 of the link 226. With the work held so that the radius bar occupies its lowermost 35 or gravity position, the position of the wheel determines the highest point in the arc to be ground. As the horizontal table 160 moves to either side of this position, the vertical table is carried upwardly by the swinging of the radius bar 176, this being indicated in 40 Figure 1 by dotted lines. Such swinging causes the wheel to grind an arc which is upwardly convex. In the position shown in Fig. 4 the wheel will grind upper arc 230 as the 45 work moves bodily in an arcuate path, always remaining parallel to its former positions. It follows from the character of the linkage that in any position of the wheel an arc of the same degree and of the same curvature will be 50 ground irrespective of the position of the wheel with regard to the pivotal center of the radius bar so long as the distance between the two pivot points of the bar remain unchanged. Thus, when the wheel 46 (Fig. 4) 55 is two inches to the right of the position indicated, the arc 230 produced at that point would have the same radius of curvature as at the center; and if the wheel were lowered two inches it would grind a concave arc two inches 60 lower than arc 230 which would be an exact duplicate of the arc 230 in distinction from being concentric therewith.

With reference to the arc 230 above described, it should be observed that the same 65 is ground concave by the upper side of the

grinding wheel 46. When the work carrier is centrally positioned, with the radius bar 176 in its gravity position, the top of the wheel 46 makes contact with the curve 230, the point of contact on the wheel lying in a vertical radius of the wheel. This is illustrated diagrammatically by Fig. 14 (Sheet 7). As the parts move relatively in an arcuate path, say to position 46^a for the wheel, the point of contact moves to a radius which is 75 angular to the vertical, the angularity of the radius being equal to the number of degrees moved by the work. Accordingly, if the work moves 90°, say to position 46^b for the wheel, the point of contact on the wheel would be 90° 80 from the vertical or on a horizontal radius of the wheel. Thus, it will be seen that the curve which is ground is dependent upon the radius r of the wheel as well as upon the radius R through which the work moves. 85 The concave arc 230 is then determined by the sum of the radius arm 176 and the radius of the wheel, or it is $R + r$.

If the wheel is now set so as to grind a convex surface, as, for example, the arc indicated by the dotted line 231, a similar condition arises but the radius of the wheel is subtracted from the effective radius of bar 176. This is due to the fact that in the initial gravity position the wheel makes contact with the work at the lower side on a vertical radius. As the radius bar swings, the point of contact of the wheel with the work moves to a radius, the angularity of which from the vertical is equal to the arc through which the work has moved. For example, if the work moves through an arc of 90° from gravity position it is obvious that the wheel will make contact with the work on a radius which is horizontal. The arc 231 defined by the point 90 of contact of the wheel with the work will then be inside of the arc of radius R (through 95 which the work moves) by a distance equal to the radius r of the wheel. Consequently, 100 when a convex arc is ground the curvature 105 thereof is determined by subtracting the radius of the wheel from the length of the radius bar 176, or it is $R - r$.

Thus it is obvious that only the effective 110 length of the radius bar 176 between its pivots plus or minus the radius of the wheel 46 determines the radius of the arc ground. It 115 is also clear that both the position of the wheel with respect to the pivot of the radius bar, and the position of the pivotal center of the bar on the upwardly extending column, have no bearing on the degree of curvature so long as the distance between the two pivot points remains unchanged. To grind any 120 convex arc as arc 232 so as to be concentric with the concave arc 230 it will be necessary to shorten the radius arm an amount equal to the difference s in radii of the two arcs less the diameter d of the wheel 46. This is 125 done by loosening the clamp 177 and sliding 130

the bar 176 through the block 175 thereby to shorten the radius arm. After tightening the clamp the vertical slide 167 may be positioned on the column without in any way affecting the degree of curvature. In grinding the arcs as illustrated feeding action may be obtained either through the hand wheel 172 to translate the path of the work vertically, or by adjustment of the wheel 44 to move the grinding wheel vertically.

In the operation of the radius grinding parts as above described, it will be observed that the special character of the motion of the work permits setting of the grinding spindle independently of the position of the radius arm, and that motion of the horizontal work table is essential to radius grinding. These two features naturally constitute the horizontal carriage of the grinding spindle and the horizontal work table as elements useful for general grinding practice as in a universal grinding machine. In such use work may be held on the vertical carrier or the horizontal table to be surfaced by the wheel or otherwise ground, making use of the automatic reciprocal travels of both the horizontal work table and the grinding spindle carriage as well as the vertical adjustment of the grinding wheel on its carriage.

To add to the universality of the machine the planetary motion may be employed by adjusting the screw 62 to produce the desired eccentricity of the spindle and by connecting the power to pulley 63 to effect rotation of the spindle carrying sleeve 56. By this arrangement holes may be ground in the usual well known manner. Also, when desired, the work table can be made motionless by applying the clamping device above described and illustrated in Figs. 12 and 13 for that purpose.

At any time the radius bar may be disconnected and the vertical table 165 may then be made fast to the member 162 on the horizontal table by suitable means for supporting the work more conveniently in access to the wheel.

In the above description of the machine it is obvious that the particular construction described produces, as regards radius grinding, a relative motion between the work carrier and the grinding wheel in a path predetermined by the relationship existing between the relative motion of the wheel and the work horizontally, or at right angles to the axis of the wheel, and the relative motion vertically, or at right angles both to the axis of the wheel and to the first motion. In the present instance the second motion is harmonically related to the first motion when the latter is uniform and it is also dependent upon said motion. It will be understood, however, that constructions other than the disclosed one may produce a similar or the same result. However, I have preferred to

use the described construction, for, by reference to the foregoing, it will be seen that I have provided a grinding machine which is particularly adapted for radius grinding by the use in common of features which are of such a structure that they are also the principal features of a universal grinding machine. Since, other embodiments of the principles herein set forth are possible by the application of well known methods of design and of mechanical skill, the invention is not to be considered as limited to the machine herein disclosed and described, but is to be considered as broadly as expressed in the terms of the appended claims.

I claim as my invention:

1. A grinding machine comprising, in combination, a support, a work table, automatic means to move said work table horizontally, a work carrier vertically slidable on said work table, suspension means from said support to said carrier, pivoted on said support and tending to hang vertically therefrom, the horizontal motion of said table swinging said carrier through an arc about the pivot of said suspension means, and means between said support and said table to hold said table in any position against the tendency of gravity to move said carrier to its lowermost position on said arc.

2. A grinding machine comprising, in combination, a support, a horizontal movable table thereon, a work carrier movable vertically on said table, means to suspend said carrier from said support, the operative relation of said means, carrier and table being such that the effect of gravity upon the carrier might tend to move the table, reversible power means to move said table, rack teeth on said table, a pinion engaging said teeth and bearing in the support, and friction means acting to prevent rotation of said pinion and tending to hold the table against motion.

3. A link grinder comprising, in combination, a base having spaced parallel ways thereon, a table reciprocable horizontally upon said ways, a vertical guideway on said table, a work carrier slidable vertically on said guideway, a grinding head adjustably mounted on one side of said table, a column rigid with said base uprising therefrom on the other side of said table, and a radius bar pivotally supported on said column and connected to said work carrier.

4. A grinding machine comprising, in combination, a bed having horizontally spaced parallel ways thereon, a table slidable longitudinally upon said ways, a grinding head adjustably mounted on said base to one side of said table, a column uprising from said bed on the opposite side of the table, a bracket having a vertical face mounted on said table, a work carriage slidable on said bracket perpendicularly to said table, and a single radius bar pivotally supported at one end on said

column and connected at its other end to said work carrier.

5. A grinder comprising, in combination, a base having horizontally spaced parallel ways 5 thereon, a table slidably mounted upon said ways, a fixture on said table having a vertical guideway, a work carrier slidably mounted on said guideway, a grinding head adjustably mounted on the base to one side of said table 10 arranged for operating upon work mounted on said table or work carrier, a column uprising from said base on the opposite side of said table, and a single radius bar pivotally supported on said column and pivotally connected to 15 said work carrier.

6. A grinding machine comprising, in combination, a bed, a table slidably mounted on said bed and having a horizontal face adapted for mounting work pieces, a universal 20 grinding head adjustably mounted on said base to one side of said table, a column extend-

ing upwardly from said bed on the other side of said table, a radius bar pivotally supported at one end on said column, a work carrier pivotally mounted on the other end of said bar, 25 and means on said table movably therewith and arranged to guide said work carrier perpendicularly to said table.

7. A machine tool having, in combination, a supporting base, a work support movable 30 rectilinearly on said base, a work carrier constrained to slide rectilinearly on said support at right angles to said support movement, and a single bar pivotally connected at one end to said carrier and pivotally connected at its 35 other end to said supporting base whereby to guide said carrier in an arcuate path during movement of the work support on the base.

In testimony whereof, I have hereunto affixed my signature.

GUSTAF DAVID SUNDSTRAND.
